EX OR D 19,596

No. 19,596.

C. E. HAVILAND.
DISH.

Patented Jan. 21, 1890.

UNITED STATES PATENT OFFICE.

CHARLES EDWARD HAVILAND, OF LIMOGES, FRANCE.

DESIGN FOR A DISH.

SPECIFICATION forming part of Design No. 19,596, dated January 21, 1890.

Application filed December 26, 1889. Serial No. 335,033. Term of patent 14 years.

To all whom it may concern:

Be it known that I, CHARLES EDWARD HAVILAND, a citizen of the United States, residing at Limoges, in the Republic of France,
5 have invented and produced a certain new and original Design for Dishes of a Table-Service, fully described and represented in the following specification and the accompanying drawing, forming a part of the same.
10 The distinguishing characteristics of the design are the shape and edge ornamentation of the plate, fully represented in the accompanying illustration, in which is illustrated by a plan view a plate embodying this design.
15 The edge 1 of the plate therein shown, which is circular in form, is divided by inward bends 2 into two series of outward curves

3 4, of different lengths and alternately arranged. The curves of each series are each provided with ornamentation composed of 20 one or more scrolls 5 or scarf's or wave-lines 6, or both, the position and formation of which are, however, different for the curves of each series.

What I claim is--

25 The design for a plate, substantially as herein shown and described.

In testimony whereof I have hereunto set my hand in the presence of two subscribing witnesses.

CHARLES EDWARD HAVILAND.

Witnesses:

ALBERT HAVILAND,
GASTON LONGEVIAL.
